JEWEL CASE

Walter F. Hess, Chicago, Ill.

Application February 6, 1950, Serial No. 7,770

Term of patent 7 years

(Cl. D86—9)

To all whom it may concern:

Be it known that I, Walter F. Hess, a citizen of the United States, residing at Chicago, in the county of Cook, State of Illinois, have invented a new, original, and ornamental Design of Jewel Cases, of which the following is a specification, reference being had to the accompanying drawings, forming a part thereof.

Fig. 1 is a perspective view of a jewel case, showing my new design; and Fig. 2 is a similar view showing the cover in open position.

I claim:

The ornamental design for a jewel case, as shown.

WALTER F. HESS.
